Frederick D. Johnson,

By Attorney

UNITED STATES PATENT OFFICE

FREDERICK D. JOHNSON, OF ROCHESTER, NEW YORK, ASSIGNOR TO HICKOK MANUFACTURING COMPANY, INC., OF ROCHESTER, NEW YORK

SUSPENDER BRACE

Application filed July 6, 1931. Serial No. 549,025.

The invention relates to improvements in suspender braces.

In the present type of suspender brace the ends of the webbing at the back of the brace are provided with buttonholes and have tape binding extending around the ends of the webbing and up the side edges thereof and terminating at the side edges opposite the upper end of the buttonhole, the core stitch of the buttonhole being knotted at the top of the buttonhole, and owing to the elastic character of the webbing and the strains thereon incident to the use of the brace, the buttonhole pulls out and the tape binding is in a frayed condition in a comparatively short time.

The object of the present invention is to eliminate the above objections and to provide a fairly substantial, non-stretchable end, thereby protecting the buttonhole stitch and eliminating the fraying of the ends of the tape binding.

A further object of the invention is to arrange the tape binding so that it will extend entirely around and fully protect the buttonhole, and to extend the ends of the tape binding to the top of the buttonhole so that the buttonhole stitching catches the ends of the tape binding, thereby obviating the necessity of knotting the core stitch of the buttonhole and at the same time assisting in securing the ends of the tape to the webbing at the top of the buttonhole.

With these and other objects in view, the invention consists in the construction and novel combination and arrangement of parts hereinafter described, illustrated in the accompanying drawings, and set forth in the claims hereto appended, it being understood that various changes in form, proportion and minor details of construction, within the scope of the claims, may be resorted to without departing from the spirit of the invention or sacrificing any of the advantages thereof.

In the drawings:

Fig. 1 is an elevation of the rear portion of a brace having the terminals of the webbing provided with the improvements of the present invention.

Fig. 2 is an enlarged detail view of one end of the webbing, showing the inner face thereof.

Fig. 3 is a similar view showing the outer face of the webbing.

In the accompanying drawings, in which is illustrated the preferred embodiment of the invention, the brace is of the ordinary style, having webbing 1 crossed at the back of the brace at 2 and secured together at the point of crossing by stitching 3 in the usual manner. The ends 4 of the webbing are provided with buttonholes 5 and have tape binding 6 extending around the end edges of the webbing and upward at the side edges thereof at opposite sides of the buttonhole to points intermediate of the ends of the buttonhole. The ends of the webbing are preferably rounded, as shown, but they may be of any other form, as will be readily understood, and the tape binding, which is of inelastic material, is provided at the sides with extensions 7 located at the inner faces of the webbing and converging upwardly to and terminating at the upper end of the buttonhole and having their terminals 8 closed or overlapped at the upper end of the buttonhole. The binding tape is secured to the webbing by stitching 9 and the buttonhole stitching catches the overlapped ends of the extensions 7, as indicated at 10, thereby obviating the necessity of knotting the core stitch of the buttonhole and at the same time assisting in securing the ends of the extension 7 to the webbing. The converging extensions 7 are preferably straight and form a substantially inverted V-shaped reinforcing upper portion, while the lower portion of the tape binding is substantially U-shaped.

The inverted V-shaped upper portion and the U-shaped lower portion completely encircle the buttonhole and the whole assembly forms substantially a non-stretchable end, as the tape binding and the extensions thereof entirely surround the buttonhole and extend entirely across the webbing at both the top and bottom of the buttonhole and eliminate the fraying and the pulling out of the buttonhole resulting from unrestrained strains on the elastic portion of the webbing at the but-

tonholes. By entirely surrounding the buttonhole with the tape binding, the buttonhole portion of the webbing is prevented from stretching longitudinally and the continual longitudinal stretching of the webbing at the buttonhole occurring in the ordinary type of suspender brace is eliminated.

While the binding and its extensions are referred to as tape, any suitable material may, of course, be employed, and the improvement may be applied with advantage to both elastic and inelastic webbing.

What is claimed is:

1. In a suspender brace, webbing provided at the end with a buttonhole and having binding extending around the end edge of the webbing and upward at the side edges thereof to a point intermediate of the ends of the buttonhole, said binding being provided at opposite sides of the webbing with extensions extending to the top of the buttonhole and having their terminals secured thereat.

2. In a suspender brace, webbing provided at the end with a buttonhole and having binding extending around the end edge of the webbing and upward at the side edges thereof to a point intermediate of the ends of the buttonhole, said binding being provided at opposite sides of the webbing with extensions converging upwardly to the top of the buttonhole and secured thereat to the webbing.

3. In a suspender brace, webbing provided at the end with a buttonhole and having binding extending around the end edge of the webbing and upward at the side edges thereof to a point intermediate of the ends of the buttonhole, said binding being provided at opposite sides of the webbing with extensions converging upwardly to the top of the buttonhole and having their terminals overlapped and secured to the webbing, with the buttonhole stitch catching the ends of the extensions.

4. In a suspender brace, elastic webbing provided at the end with a buttonhole and having binding extending around the end edge of the webbing and upward at the side edges thereof to a point intermediate of the ends of the buttonhole, said binding being provided with extensions located at the inner face of the webbing and converging upwardly to the top of the buttonhole and secured thereat to the webbing, the binding and the extensions being inelastic and completely surrounding the buttonhole and forming a substantially non-stretchable end to the webbing.

5. In a suspender brace, elastic webbing provided at the end with a buttonhole and having binding extending around the end edge of the webbing and upward at the side edges thereof to a point intermediate of the ends of the buttonhole, said binding being provided with extensions located at the inner face of the webbing and converging upwardly to the top of the buttonhole and over-

lapped thereat and secured to the webbing at the said top of the buttonhole, the buttonhole stitch catching the overlapped ends of the extensions and the said extensions and binding forming an inelastic reinforcing element completely surrounding the buttonhole and extending entirely across the webbing at the top and bottom of the buttonhole to form a substantially non-stretchable end to the webbing.

6. In a suspender brace, elastic webbing having a rounded end edge and provided at the end with a buttonhole and having tape binding extending around the end edge and up the side edges of the webbing and provided with extensions converging to the upper end of the buttonhole and overlapping thereat and secured to the webbing, the extensions forming an inverted V-shaped portion and the binding forming a lower substantially U-shaped portion, the V-shaped and U-shaped portions forming a loop entirely surrounding the buttonhole and rendering the end of the webbing substantially non-stretchable to prevent fraying of the binding and pulling out of the buttonhole by longitudinal stretching of the elastic.

In testimony whereof, I have hereunto affixed my signature this 3rd day of July, 1931.

FREDERICK D. JOHNSON.
